UNITED STATES PATENT OFFICE.

CHARLES F. MATHEWS, OF GOLDFIELD, COLORADO; J. B. SCHMALZRIED ADMINISTRATOR OF SAID CHARLES F. MATHEWS, DECEASED.

BANK PROTECTOR.

Application filed September 10, 1921. Serial No. 499,812.

To all whom it may concern:

Be it known that I, CHARLES F. MATHEWS, a citizen of the United States, residing at Goldfield, in the county of Teller and State 5 of Colorado, have invented certain new and useful Improvements in Bank Protectors; and I do hereby declare the following to be a full, clear, and exact description of the invention, such as will enable others skilled 10 in the art to which it appertains to make and use the same.

The present invention relates to protective devices particularly for use in banks, offices, and other financial institutions where it is 15 desired to protect the clerks and officers and also the moneys which are handled in relatively large amounts.

An object is to provide a grating or partition which may be used in a bank or the 20 like, and which has the ordinary windows or openings through which business may be transacted between customers and clerks, and to provide such partition or grating with protecting devices to facilitate the 25 quick closing of such windows and render the windows and the partition bullet-proof and proof against access of robbers or others who endeavor to gain unauthorized access to the clerks and money.

Another object is to provide means between a plurality of such windows for effecting the complete closure of all of the windows from any one of the windows or from 30 various other points within the enclosure so as to completely protect and close off the 35 space within the partition from the outer compartment of the bank.

The invention further provides a novel means for securely locking the entrance door 40 against opening to confine robbers or the like within the bank room as soon as their presence is discovered, which door securing means is designed to be operated from various parts of the building or enclosure; the 45 door operating means being also connected for operation upon the closing of any one or more of the window protecting shutters.

The invention further aims at the provision of a protecting apparatus of a character 50 which embodies the above characteristics, and which may be tripped or actuated by manually pulling on a handle, by operation of the foot, or by electrical means controlled from a switch at a distance from the 55 seat of operation, the apparatus necessarily

combining these features for the protection of the individuals in and about the enclosure, so that the least bodily movements are required for tripping the mechanism.

With these and further objects in view as 60 will in part hereinafter become apparent and in part be stated, the invention comprises certain novel constructions, combinations and arrangements of parts as subsequently specified and claimed. 65

In the accompanying drawings,—

Figure 1 is a side elevation of a partition or enclosure such as used in banking and the like institutions constructed according to the present invention, the view also showing a 70 door and locking means therefor controlling the entrance and exit of patrons and other individuals of the institution.

Figure 2 is an enlarged, fragmentary view, partly in section, of the upper portion of the 75 partition or enclosure, showing a window and the various mechanisms associated therewith for supporting and releasing a protecting shutter.

Figure 3 is a vertical section taken 80 through the structure of Figure 2, substantially on the line 3—3 thereof, showing the window in open position of use.

Figure 4 is a horizontal section taken substantially on the line 4—4 of Figure 2, and 85 looking downwardly toward the bottom part of the window.

Figure 5 is an inner side elevation of the lower portion of the partition at the bottom part of the window, taken reversely to the 90 showing in Figure 2.

Figure 6 is a fragmentary, enlarged section taken through the lower portion of the window and adjacent parts on the line 6—6 of Figure 4, showing the connecting means 95 for actuating adjacent shutters upon the dropping of one of the shutters.

Figure 7 is a diagrammatic view, partly in elevation, of the operating means interconnecting the shutters and door lock, and 100 illustrating the various means for releasing the shutters.

Figure 8 is a fragmentary, perspective view of one of the trip devices, showing a 105 shutter cushioning means.

Referring to the drawings by numerals, the general arrangement is illustrated in Figure 1, wherein the partition or dividing wall may be extended in a straight line, as shown, or may be extended in various an- 110

2
gular formations, or in circular form, to provide one or more enclosures as is required in banking and like institutions where large sums of money are handled. In 5 the present instance, the partition is composed of sheet metal plates 10, which are of suitable thickness to withstand ordinary impact of bullets and the like to prevent penetration of the sheets 10 and thus protect the 10 occupants of the enclosure. The sheets 10 form a side wall and are supported upon posts 11, which are preferably of tubular construction and which rise from the floor of the building to a distance slightly above 15 the sheets 10.

As best shown in Figures 4 and 5, the plates 10 are secured across the outer sides of the posts 11, and at suitable points the plates 10 are apertured or interrupted to 20 form windows or openings through which money and other articles may be passed between patrons outside of the enclosure and attendants within the enclosure. For this purpose, the sheet metal wall may be provided with an outstanding shelf 12 extending 25 across the lower edge of the window and supported in position by clamps 13 which project rearwardly through the metal wall and are bound upon a cross piece 14 secured between adjacent posts 11 beneath 30 the window. At each window, as shown in Figure 4, the opposed posts 11 are provided with guide blocks or channel members 15, which are preferably interposed between 35 the posts 11 and the outer metal wall, and which have vertically extending grooves 16 upon the inner faces of the guide blocks for a purpose which will hereinafter appear. The window in the metal wall may be 40 closed by a transparent pane 17, of glass or like material, which has one or more openings or notches 18 in its lower edge of sufficient size to pass money and small articles back and forth through the window. 45 The blocks 15 carry upon their inner grooved faces a vertically slidable shutter 19, adapted to drop by gravity to close the window. The window opening is further defined by side pieces 21, which fit against 50 the inner opposite sides of the posts 11, and which have rabbets or seats 22 therein registering with the inner grooved faces of the blocks 15 and into which the lateral edges of the shutter 19 are adapted to slidably 55 engage. The grooves 22 form retaining shoulders for the shutter to hold the latter in correct position during its vertical sliding movement, and to prevent the bursting in of the shutter incident to impact of blows 60 of heavy tools or the like.

The window opening is further closed by an inner transparent panel 23, of glass or the like, which is seated at the inner edge portions of the side pieces 21 of the window frame. The panels 17 and 23 provide an

enclosed space within which the shutter 19 may rise and fall for closing the window against impact of heavy articles, bullets, and the like.

The partition may be provided with any 70 suitable number of these windows, and each window has a corresponding construction and protective mechanism.

The shutter 19 is normally held in raised position out-of-the-way by a hook 24, 75 which is formed on the short end of a latch lever 25, the latch lever being pivoted at 26 near its hook end. The hook 24 of the latch lever is forked or bifurcated at its lower end, as shown in Figure 3, and straddles the upper end of the shutter 19, when the latter is raised. The shutter is provided at opposite sides with outstanding studs 27, which engage the hook 24 for normally supporting the shutter in raised position. 80 The latch lever 25 rises above its pivotal support 26, and is connected at its upper end to an operating or trip cord 28, which extends laterally from the lever 25 toward an adjacent post 11. As shown in Figure 2, 85 the cord 28 passes into an angle iron 29, carried upon the upper end of the post 11, and over a pulley 30, which is pivoted in the angle iron 29. The cord 28 is trained downwardly over the pulley to a point near the floor where the cord is connected to a treadle 31 which extends transversely beneath the window and which is adapted to be engaged by the foot of an operator when it is desired to trip the latch lever 25. The treadle 31 is pivoted at one end to a bracket 32, fixed to the floor near one post 11, and the treadle extends along the partition and across the opposite post and projects through a slot 33 formed in the lower end 90 of a tube 34. The tube 34 constitutes a housing in which a drop weight 35 is mounted. The weight 35 is normally held in the top of the tube by a latch bolt 36 forming the end of a core of a solenoid 37, 95 which may be energized by closing a circuit through the wires 38. The wires 38 may, of course, extend to any suitable point where access may readily be had for closing the circuit. When the solenoid is energized, the weight 35 is released, and the latter drops 100 downwardly through the tube 34 onto the outer end of the treadle 31 for depressing the same and tripping the latch 24. 105

Each slide block 15 is provided, near its lower end, with trip pins 39, which lie in the path of the shutter 19, and which are adapted to be struck when the shutter reaches its lowered position. The pins 39 are carried on U-shaped slides 20 with spaced arms slidable in the lower ends of the grooves 16, one arm of each slide 20 being connected to a cable 40 which extends upwardly in a groove 16 behind the metal wall and over a pulley 41 in a T-coupling 110 115 120 125 130

incorporated in the post 11. The cable 40 is trained in the piping or cross braces 42 of the partition to the next window. The other end of each cable 40 is connected to the hook 24 of the next window at a point below the pivot 26 thereof, as shown in Figure 7. When the cable 40 is drawn taut, the hook 24 is released from the pin 27, and the next adjacent shutter is dropped. The 10 cable 40 also has an extension 43 which may be carried across the upper portion of the window and over a pulley 44 and provided with a handle 45 depending at a suitable height and in a suitable position for easy 15 grasping of individuals behind the partition. All of the shutters 19 are arranged to successively draw on the cables 40 and to thus effect the successive closing of all 20 of the windows throughout the length of the partition.

As a means for initially opening or releasing one of the hooks 24, a cable 46 is connected to the upper end of each latch lever 25, and the cable is trained downwardly over a pulley 47, and is suspended at one side of each window. The lower end of the cable 46 has a handle 48 in proximity to the attendant, so that the handle may be quickly grasped and depressed for swinging the latch lever. The cables 40 are normally drawn taut or raised into position for permitting the hooks 24 to latch by a spring 49, which is carried upon the end of the partition and which engages the said partition at one end and is connected to the cable 40 at its other end, the cable 40 passing axially through the spring. If desired, the extensions 43 of the cables 40 may be attached directly to the latches 24 to form continuations of adjacent cables 40 so as to provide a straight line pull on all of the latches 24 by the spring 49.

The end trip pin 39, or the pin near one end of the partition, is preferably connected to a cable 50, which is carried over a pulley 51 and through the upper part of the partition to a latch lever 52, which is pivoted at 53 over a revolving or turnstile door 54. The door 54 comprises the entrance to the building, and is provided with a circular plate 55 on its upper end having closely spaced-apart notches 56, and into which is adapted to drop the toothed end 57 of a shutter or latch plate 58, which is normally suspended above the door 54. When the last shutter 19 drops, the cable 50 is drawn taut, and the latch lever 52 is swung upon its pivot 53 in position to release the hook 59 from the outstanding pin 60 of the latch plate 58, permitting the latter to drop into engagement with the door 54 and to hold the door from further turning.

The imperforate wall 10, which comprises 65 the body of the partition, may also be pro-

vided at suitable points between or at the sides of the windows with doors 61 hinged at 62 and provided in the body portions of the door with relatively narrow slots 63 extending at angles to one another as desired, and of sufficient size to permit the projection of the muzzles of guns or other suitable weapons through the door when closed for protecting the bank and its attendants from robbers or the like. These doors 61 may be opened by the attendants within the enclosure to receive packages therethrough, or to hold prolonged conversations with parties on the outer side of the partition when necessary.

The posts 11 may be of any suitable height or construction, and may be supported directly upon the floor, as shown, or may be mounted in any other suitable manner found desirable and convenient according to conditions met with in installation. The guide block 15 may have any desired number of grooves therein as required for meeting various conditions of manufacture, stability and installation.

If desired, the slide 20 may be cushioned to absorb shock incident to the falling of the shutter 19, and this may be accomplished in various ways, such as shown in Figure 8, where the free arm of the slide 20 is attached to a spring 64 which is connected at its lower end 65 to the arm and lies in the adjacent groove 16. The upper end of the spring 64 is secured at 66 to the block 15 for supporting the slide 20 by the spring, and permitting yielding of the latter when the shutter descends.

What is claimed is:

1. In a protective device for banks and the like, a partition wall having a plurality of windows therein, a turn-stile door controlling passage to the enclosure of the bank, a plurality of gravity-actuated devices associated with the windows and the turn-stile for controlling closing of said windows and holding said turn-stile from operation, retaining means for said gravity-actuated devices, and connections between all of said devices adapted to operate upon the dropping of any selected device for effecting the dropping of all of the devices to occasion gravity closing of the windows and locking of said turn-stile against rotation.

2. A protective partition for banks and the like comprising a wall having a plurality of windows therein through which business may be transacted, a gravity shutter housed in the wall above each window, hooks carried by the wall, one for each gravity shutter, means urging said hooks into interlocking engagement with said shutters for maintaining the same raised, individual means for releasing said hooks to permit the shutters to drop, and trip mechanism between the shutters and adjacent

hooks for releasing the latter upon the dropping of any selected shutter.

3. In a protective partition for banks and the like, a wall having window openings therein through which business may be transacted, a shutter for each window opening, supporting devices carried by the wall above said windows and adapted to engage the shutters for normally maintaining the same raised, individual operating means for releasing said retaining means to permit the shutters to drop into closed position, and means operable upon the dropping of the individual shutters for releasing adjacent retaining means, whereby all of said windows may be closed upon the closing of any selected window.

4. In a protective device for banks and the like, a door controlling passage into and out the bank enclosure, a gravity device for locking said door closed, a partition in said enclosure having windows therein through which business may be transacted, gravity devices for controlling closing of said windows, independent releasing means for said gravity devices adapted to normally maintain the same raised and adapted to release the same for causing locking of the door and closing of the windows, and interconnections between said gravity devices whereby individual actuation of one of said devices is adapted to actuate all of said devices.

5. A protective partition for banks and the like comprising a wall having a plurality of windows therein through which business may be transacted, a shutter slidably disposed over each window and adapted to drop by gravity for closing the same, a hook pivotally mounted over each window and adapted for interlocking engagement with the adjacent shutter for maintaining the latter in raised position, pull cords connected to said hooks for individually releasing the same, cords connecting said hooks together for simultaneously operating the same to release all of the hooks from any of said shutters, and other pull cords connected to said hooks and to adjacent windows for contact with the shutters when dropped.

In testimony whereof I affix my signature in presence of two witnesses.

CHARLES F. MATHEWS.
